(57) CLAIM

The ornamental design for reveal guide tool, as shown and described.

DESCRIPTION

FIG. 1 is a perspective view of a reveal guide tool showing our new design.

FIG. 2 is a top plan view as viewed from the top in FIG. 1, rotated clockwise approximately 45°.

FIG. 3 is a side elevation as viewed from the bottom in FIG. 2; the opposite side view being a mirror image.

FIG. 4 is a side elevation as viewed from the right in FIG. 2; the opposite side view being a mirror image.

FIG. 5 is a bottom plan view as viewed from the bottom in FIG. 3.

FIG. 6 is a perspective view of a second embodiment of reveal guide tool showing our new design.

FIG. 7 is a top plan view as viewed from the top in FIG. 6 and rotated clockwise approximately 45°.

FIG. 8 is a side elevation as viewed from the bottom in FIG. 7, the opposite side being a mirror image.

FIG. 9 is a side elevation as viewed from the right in FIG. 7, the opposite side being a mirror image; and,

FIG. 10 is a bottom plan view as viewed from the bottom in FIG. 8.
